(57) **CLAIM**

The ornamental design for storage rack for headphones, as shown and described.

DESCRIPTION

FIG. 1 is a left, front perspective view of a first embodiment of a storage rack for headphones according to my design, the right, front perspective view being mirror symmetrical; FIG. 2 is a right, side perspective view thereof, the left, side perspective view being mirror symmetrical;

FIG. 3 is a front view thereof;

FIG. 4 is a left side view thereof, the right side view being mirror symmetrical;

FIG. 5 is a top view thereof;

FIG. 6 is a bottom view thereof;

FIG. 7 is a right, side perspective view thereof showing a possible environment, the left side perspective view being mirror symmetrical; and

FIG. 8 is a right, front perspective view thereof showing a possible environment, the left, front perspective view being mirror symmetrical.

FIG. 9 is a left, front perspective view of a second embodiment of the storage rack for headphones according to my design, the right, front perspective view being mirror symmetrical;

FIG. 10 is a right, side perspective view thereof, the left, side perspective view being mirror symmetrical;

FIG. 11 is a front view thereof;

FIG. 12 is a left side view thereof, the right side view being mirror symmetrical;

FIG. 13 is a top view thereof;

FIG. 14 is a bottom view thereof;

FIG. 15 is a right, side perspective view thereof showing a possible environment, the left side perspective view being mirror symmetrical; and,

FIG. 16 is a right, front perspective view thereof showing a possible environment, the left, front perspective view being mirror symmetrical.

The broken lines are for illustrative purposes only and form no part of the claimed design.
